UNITED STATES PATENT OFFICE.

ARTHUR R. CURTIS AND CHARLES E. OATHOUT, OF CLEVELAND, OHIO, ASSIGNEES TO
THE KAYNEE COMPANY, OF CLEVELAND, OHIO, A CORPORATION OF OHIO.

PRINTING-MACHINE.

1,377,754.

Specification of Letters Patent. Patented May 10, 1921.

Application filed May 9, 1919. Serial No. 295,915.

To all whom it may concern:

Be it known that we, ARTHUR R. CURTIS and CHARLES E. OATHOUT, citizens of the United States, and residents, respectively, 5 of Cleveland, in the county of Cuyahoga and State of Ohio, and Cleveland, in the county of Cuyahoga and State of Ohio, have invented a certain new and useful Improvement in Printing-Machines, of which 10 the following is a full, clear, and exact description.

This invention relates to a printing machine, and has for its object to improve the efficiency and utility of certain kinds of 15 printing machines, for example, those adapted to print data repeatedly on severable portions of a card or strip.

In certain industries, as for example, in the garment making industry, it is customary, especially when the operators are paid on a piece-work basis, to attach to 20 bundles of pieces which are to be made up into garments, cards composed of tabs or sections usually separated by scored lines so 25 that they can be detached by the operators, these sections having printed thereon, certain identification data common to all the sections of a card, as, for example, data identifying or descriptive of the garments, 30 such as the lot number, size, and the number of pieces of which a garment or bundle to which the card is attached is composed.

This data being common to all the sections of a card, can be readily printed thereon, 35 and it is customary for garment manufacturers to print this data on the cards by a common and simple form of printing machine which feeds the card, step by step along the printing platen, and which at the 40 same time prints or stamps the data common to all the sections of the card successively on the different sections.

However, it is desirable that the different sections of a card be provided in addition 45 to this common data, with different or varying data as to the prices to be paid the different operators for the different operations that they are to perform. Hence it is customary for the garment manufacturer to 50 have employees write price data for the different operations on the different sections of each card after the cards have been run through the printing machine which prints thereon the same or common data referred 55 to above. This ordinarily completes the in-

formation necessary to be provided on a card for attachment to a bundle of pieces.

In practice, the bundle is passed from operator to operator, each of whom performs a given operation on the pieces of the bundle, 60 and when each has completed his or her work, the operator detaches from the card a section or tab corresponding to the operation which this operator has performed, 65 which tab shows the price that the operator is to be paid for the operation, and at the end of the day the operator will have a series of these tabs which will be turned into the office for use in determining the amount that this operator has earned during the 70 day, the tabs that the operator turns in, being a check on the stubs of the cards which were turned into the office from another source.

This method of making up the cards, i. e., 75 by printing the common data on the different sections and writing the different data on the sections is not only exceedingly expensive in a garment making establishment of large size, but errors are liable to be, and frequently are made.

Furthermore, the cards such as above described, and designed to be attached to bundles of parts or pieces which are to be made into garments, obviously are not all required to have the same number of printed 85 tabs or sections since certain bundles require more operations than others.

By the machine which we have provided, 90 the necessity for writing the data, which is different for the different sections, is obviated, mechanism being provided to print on the different sections the varying data, at the same time that there is printed thereon the data which is common to all of them.

As a further feature of the invention, 95 provision is made for automatically stopping the printing machine or the movement 100 of the printing head after a predetermined number of printing operations have been performed on the cards, and in fact we provide means whereby as successive cards are run through the machine, each will be subjected to the desired number of printing operations irrespective of the number which is predetermined, and when a particular 105 card has received a number of printing impressions, the printing operations will automatically stop though the cards which preceded it and which follow may receive a different number of printing operations. 110

Another important feature of the invention resides in the manner of constructing the printing head, and especially the support for the printing members which are preferably in the form of wheels, and which print on the different sections of a card the same data and the varying data, it being one of the specific objects to provide means whereby the printing wheel which carries the type for printing the varying data can be readily and quickly removed from the printing head without disturbing or making it necessary to remove the printing wheels which print the recurring data.

The invention may be further briefly summarized as consisting in certain novel details of construction, and combinations and arrangements of parts which will be described in the specification and set forth in the appended claims.

In the accompanying sheets of drawings wherein we have shown the preferred form of the invention, Figure 1 is a top plan view of a machine constructed in accordance with our invention, parts being broken away, and other parts being in section; Fig. 2 is a side elevation of the same; Fig. 3 is a fragmentary view showing a portion of the machine in rear elevation; Fig. 4 is a view on an enlarged scale, showing partly in elevation and partly in section, some of the printing wheels, and showing the manner in which that wheel which prints the varying data may be readily removed; Fig. 5 is a view of the same partly in end elevation and partly in section; and Fig. 6 is a view of a card such as may be printed with the machine.

The machine includes in this instance, a base or stand 10, on which is mounted a horizontal bed or frame 11. A movable printing head designated in its entirety by the reference character 12, is in this case adapted to be moved up and down, or swung vertically, and to that end it is carried by an oscillating arm 13, secured to a rock-shaft 14, mounted in suitable bearings on the frame, this rock-shaft having a rearwardly extending arm 15, to the rear end of which is connected an actuating link 16, whose upper end is connected at an off-center point, as clearly shown in Fig. 2, to a rotary actuating disk 17, which is mounted on a shaft 18, likewise supported in suitable bearings on the frame of the machine. The shaft is driven by a gear 19, engaged by a driving pinion 20, secured to a shaft 21 which is supported on the frame between the shaft 18 and the rock-shaft 14.

Mounted on the shaft 21 is a driving pulley 22 which is normally loose on the shaft and can be moved endwise thereon. This pulley rotates the shaft when it is pressed against a clutch disk 23 which is fixed to the shaft.

The pulley is moved into and out of engagement with the clutch disk 23 by a lever 24, on a rock-shaft 25, suitably mounted in bearings on the bed or frame 11, this rock-shaft being provided on its rear end with a bell-crank, one arm 26 of which projects upwardly and inwardly, and is provided at its free end with a roller 27 engaging the face of the crank disk 17. This disk prevents disengagement of the pulley and disk 23, except when the roller 27 drops into a slot 28 of the crank disk 17. The other arm 29, of the bell-crank has connected to it a spring 30 which tends to rock the bell-crank and the rock-shaft 25 so as to disconnect the pulley 22 and disk 23, and stop the printing operations. The pulley is pressed into engagement with the disk 23 by a substantially vertical push rod 31, and a pedal 32, designed to be actuated by the operator, this push-rod being adapted to engage on the under side of bell-crank arm 29, but when moved from beneath said bell-crank arm in the manner hereinafter explained, the spring 30 pulls the driving pulley away from the disk 23 when the opening 28 of the crank-disk 17 comes opposite the roller 27, and thus allows the roller to drop therein. The opening 28 which times the stopping of the machine is so positioned that the machine will always come to a stop with the printing head elevated.

The printing head 12, previously referred to, and stated to be mounted on the free end of arm 13, has two side plates 33, 33, connected together at their front ends by a cross-bar 34. The printing members carried by this head are preferably in the form of wheels including normally stationary wheels 35, with printing type on their peripheries, and one or more, but in this instance, one movable wheel 36 which is designed to be moved one step during the cycle of each printing operation, this wheel 36 being connected by a pin 37 to a ratchet disk 38, the pin 37 projecting through the ratchet disk and into a slot on one side of the printing wheel 36. This printing wheel has peripheral notches or slots into which are set removable type slugs 39, preferably held in place by rings secured to opposite sides of the wheel.

The printing wheels 35, together with suitable spacers 40, are mounted on a non-rotating fixed shaft 41 supported by one of the side plates 33, and by a plate 42 extending from the front bar 34 to the rear part of the head. These wheels 35 which are used to print the common matter on all the sections or tabs of the cards to be printed, do not normally rotate on the shaft 41, being held from movement by pawls 43, pressed into peripheral notches of these wheels by leaf springs 44, mounted on the rear part 45 of the printing head, but the

wheels may be turned when it is desired to change the data to be printed on the cards, by handles 46, projecting outwardly from the peripheries of these printing wheels. 5 These wheels 35 are permanently mounted in the head as there is no occasion for removing them unless they should become broken.

The movable printing wheel 36, which as 10 before stated, is moved one step in the cycle of each printing operation, and which is utilized to print the varying matter or data on the cards, is mounted on a short shaft 47, which is supported in part by one of the side 15 plates 33 of the printing head, and in part by the shaft 41, the shaft 47 having a pilot 48 entering into an opening or socket at the end of the shaft.

To permit the quick removal of the printing wheel 36 without disturbing the printing wheels 35, or the shaft 41 on which they are mounted, this shaft 47 is made movable in endwise direction, and it is designed to be shifted by the operator outwardly beyond 25 the plane of the wheel 36 through the medium of a pin 49 which projects outwardly from the shaft 47 through a helical slot 50 in a boss or equivalent member 51 on the inner side of the adjacent plate 33 of the 30 head. It will be obvious, especially by reference to Fig. 4, that it is only necessary for the operator to move the pin 49 along the spiral slot 50 to shift the shaft 47 beyond the printing wheel 36, thus permitting the 35 latter to be removed edgewise from the head. Usually there will be provided a separate printing wheel 36, for each of the different sizes or styles of garments, and the construction which we have provided, allows 40 the printing wheel 36 to be quickly changed, thus enabling cards for the different types and sizes of garments to be printed without any material delay in adapting the machines therefor.

45 The printing wheel 36 is held from accidental movement on the shaft 47 by a spring pressed pawl 52 engaging peripheral notches of the wheel, and it is moved one step, *i. e.*, the distance from one printing slug to the 50 next during each printing cycle by a fixed pawl 53 (see Figs. 1 and 2) stationarily mounted on a standard 54 of the bed or frame, and so arranged that on each up stroke of the printing head this pawl will 55 engage a tooth of the ratchet disk 38 at the side of the printing wheel 36, and move the ratchet disk and printing wheel the distance previously stated, *i. e.*, so as to bring to printing position the slug next to that which was 60 in printing position on the previous down stroke of the printing head. Beneath the printing head there is a platen 55, on which the printing is done, and the cards are moved step by step over the platen and along a 65 guideway indicated at 56, by a pair of co-

acting rollers 57 and 58, designed to engage one edge of the cards. At the side of one of these rollers 57 is a ratchet disk 59, and on each up stroke of the printing head this ratchet disk and the roller associated with it are given a movement sufficient to feed the card a distance equal to a printing space on the card. This is accomplished by a pawl 60, which is pivoted at its rear ends to an arm 61, secured to the rock-shaft 14 carrying the arm 13 to which the printing head is secured. The construction is such that on the down stroke of the printing head the pawl moves forwardly, and on the up stroke the pawl is moved rearwardly a sufficient distance to move the ratchet disk and card feeding roller 57 so as to feed the card a distance equal to one printing space.

The roller 58 which coöperates with the feeding roller 57, is carried on a pivoted 85 arm 62, to which is fixed a hand lever 63, to which is connected a spring 64, which normally presses the roller 58 yieldingly against the roller 57. The operator has simply to press the lever 63 rearwardly to separate 90 the rollers and permit a card to be placed between the same.

In Fig. 6 we have shown a card, in the printing of which our machine has special utility as before explained. This card has 95 a series of tabs or sections 65, separated from each other by scored lines 66, and from stubs 67 by a scored line 66^a. The stubs and adjacent ends of the tabs or sections 65 have printed thereon, numbers 68, indicating the 100 several garment making operations, there being a space on each stub in which may be placed a set of characters 69 indicating the operator. To the right of the operation numbers 68, the data is adapted to be printed 105 by this machine in column form, the data in columns 70, 71 and 72 being common to all the sections or tabs of a card, this data being printed by the normally stationary or normally non-rotating printing wheels 35, 110 four of which we have shown in Fig. 4. The price data appearing in column 73 varies for the different tabs or sections, and therefore for the different operations to which the different sections are devoted, this data 115 being that printed by the step by step movable printing wheel 36, which is mounted so that it can be easily removed edgewise in the novel and effective manner already described, and which is given its step by step 120 movement by the very efficient mechanism explained above.

The card shown in Fig. 6 has the common or constantly recurring data and the varying data printed on all the tabs or sections, 125 but it may be desirable that part only of the tabs of a card be printed, and we have made provision in our improved printing machine for automatically stopping the operation of the printing head after successive 130

series of printing operations, with successive series having the same or different numbers of separate printing operations. To that end we have provided automatic stopping mechanism including a rotary dial 74, suitably supported on the frame of the machine, which dial has on its under side, ratchet teeth 75, adapted to be engaged so as to move the dial step by step by a pawl 76 which is pressed up into engagement with the teeth by a spring 77, and is mounted on an arm 78, carried by the rock-shaft 14, the whole being so constructed that when the machine is in operation this dial will be stepped along in predetermined relationship with the movement of the printing head and card feeding rolls. It will be observed that the dial is provided near its periphery with openings or sockets 79 numbered consecutively, and adapted to receive throw-out pins 80, which can be positioned to stop the operation of the machine after successive series of printing operations, the number of printing operations in each series depending upon the spacing of these pins, which spacing is predetermined and bears a fixed relation to the number of printing impressions that are to be printed on cards which are successively fed through the machine.

These throw-out pins 80 are moved in a circle by the rotating dial, and when each reaches a given position it engages and moves the beveled end 81 of a trip lever 82, pivoted between its ends at 83 on a standard fixed to the frame of the machine, the lower end 84 of this lever being just beneath the bell-crank arm 29 previously referred to, and at the rear of the upper end of the push rod 31 when it is in engagement with the lower side of this bell-crank arm.

Assuming that the operator has a series of cards to be printed, which are to have different numbers of tabs printed with the constant and varying data, the operator will set a pin at the zero position, and other pins in the openings around the periphery of the disk, the spacing depending upon the number of printing operations which are to be given to the successive cards.

The operator will then place a card in the machine between the rolls and start the operation by pressing the foot pedal, the upper end of the push rod then engaging under the bell-crank arm 29, as shown in Fig. 2.

The machine will operate repeatedly and rapidly, and when the predetermined number of printing operations have been impressed on the card referred to, the pin next to the pin in zero position will engage the end of trip lever 82, and rock it sufficiently so that its lower end will push the upper end of rod 31 from beneath the bell-crank arm 29, so as to stop the machine.

The operator will next place the second card in the machine, and again start the

operation, and after a predetermined number of printing operations, determined by the position of the second pin beyond the zero pin, the machine will be automatically stopped, and this will be repeated for the different cards of the set or series.

In explaining the construction and operation we have for the sake of clearness referred solely to the printing of cards adapted for use in the garment making industry, but it will be obvious that the machine may be used for printing cards or blanks other than those of the type referred to adapted to be used for the purpose and in the manner explained, and while we have explained only the preferred construction, it will be obvious that changes may be made in details of construction and arrangement without affecting the principal features of the invention and the desirable functioning of the machine embodying such features.

Having described our invention, we claim:

1. In a printing machine, a movable printing head having a plurality of type carrying printing wheels, part thereof being fixed in said head for rotary adjustment only, and part coaxial with the first-named being removably mounted in said head.

2. In a printing machine, a platen, a plurality of printing wheels, a pair of coaxial shafts for supporting said wheels, each shaft supporting part of the wheels, one of said shafts being mounted for endwise movement away from the wheel or wheels supported thereon.

3. In a printing machine, a platen, a printing head movable toward and from the platen, two shafts coaxially mounted in said head, one being movable in an endwise direction away from the other, and a plurality of printing wheels, part mounted on one shaft and part on the endwise movable shaft.

4. In a printing machine, a platen, a printing head movable toward and from the platen, two shafts coaxially mounted in said head, one being movable in an endwise direction away from the other, and a plurality of printing wheels, part mounted on one shaft and part on the endwise movable shaft, the part on the first mentioned shaft being normally stationary, and means for moving the part on the second mentioned shaft during the cycle of each printing operation.

5. In a printing machine, a platen, a plurality of printing wheels, a pair of coaxial shafts for supporting said wheels, each shaft supporting part of the wheels, one of said shafts being stationary and having a bearing for the second, and the second being mounted for endwise movement away from the first-named.

6. In a printing machine, a platen, a plurality of printing wheels, a pair of coaxial shafts supporting the said wheels, one of said shafts having a bearing member with

a slot, and said shaft having a shifting member extending through said slot, said slot being so disposed that when the shifting member is moved along the same said shaft 5 is moved axially away from the other shaft.

7. In a printing machine, a platen, a movable printing member, means for actuating said printing member, and means for automatically rendering the actuating means 10 operative after each of a number of series of printing operations, each series composed of a predetermined number of operations which may be the same or different than the number in the other series.

15 8. A printing machine comprising a platen, a movable printing member, actuating means for causing printing impressions to be made, means for starting the operation of the printing member, and means for automatically stopping the actuation of the 20 printing member so that successive blanks will receive only predetermined numbers of printing impressions which may be of like or unlike value.

25 9. A printing machine comprising a platen, a movable printing member, actuating means for causing printing impressions to be made, means for starting the operation of the printing member, and means for automatically stopping the actuation of the 30 printing member so that successive blanks

will receive only predetermined numbers of printing impressions, said automatic means involving devices by which successive blanks may receive printing impressions of the 35 same or different predetermined or selected numbers.

10. In a printing machine, a platen, a movable printing member, means for actuating said printing member, means for automatically rendering the actuating means 40 operative after a set of successive printing operations, and means adapted to be given a preliminary setting for controlling the first-named means whereby successive sets 45 of printing operations may vary in numbers of operations.

11. A printing machine comprising a movable printing member, means for actuating the same and having a clutch by which the 50 printing member is started and stopped, a clutch controlling means adjustable for a plurality of succeeding sets of printing operations and embodying mechanism by which the printing impressions are stopped after 55 each of a series of printing operations which may vary in number with respect to any other series.

In testimony whereof, we hereunto affix our signatures.

ARTHUR R. CURTIS.

CHARLES E. OATHOUT.
